CLAIM

We claim the ornamental design for a display screen with graphical user interface, as shown and described.

DESCRIPTION

FIG. 1 is a front view of a display screen with graphical user interface showing the new design;

FIG. 2 is a second embodiment thereof;

FIG. 3 is a third embodiment thereof; and,

FIG. 4 is a fourth embodiment thereof.

The outermost broken line perimeter illustrates a display, screen, or the like or portion thereof and forms no part of the claimed design. All other broken lines illustrate features of a display screen with graphical user interface that form no part of the claimed design.
